UNITED STATES PATENT OFFICE.

WILLIAM F. JONES, OF DIALVILLE, TEXAS.

BUMPER FOR LOG-WAGONS.

1,079,859.

Specification of Letters Patent. Patented Nov. 25, 1913.

Application filed March 27, 1913. Serial No. 757,101.

To all whom it may concern:

Be it known that I, WILLIAM F. JONES, a citizen of the United States, and a resident of Dialville, in the county of Cherokee 5 and State of Texas, have invented a new and Improved Bumper for Log-Wagons, of which the following is a full, clear, and exact description.

My invention relates to bumpers in use on 10 log wagons, and has reference more particularly to a device mounted to roll on a wagon bolster and adapted to collapse below the carrying surface of the bolster.

An object of the invention is to provide 15 an inexpensive, simple, solid and easily operated bumper which will prevent transverse and longitudinal displacement of a load of logs when in operative position.

A further object is to provide a bumper 20 which will collapse when desired and thereby aid to quickly discharge a load from a wagon.

The invention consists of the construction 25 and combination of parts to be more fully described hereinafter and fully set forth in the claims.

Reference is to be had to the accompanying drawings forming a part of this specification, in which like characters indicate corresponding parts in all the views and in which:

Figure 1 is a side elevation of an end of 35 a bolster embodying my invention; Fig. 2 is a similar view with the bumper collapsed, having one side of same broken away to show the detail of construction; Fig. 3 is a plan view of Fig. 1; Fig. 4 is a sectional view on line 4-4, Fig. 1; and Fig. 5 is a plan view of the key.

In the appended drawings, 6 represents 40 a bolster on the end of which is mounted a bumper 7 formed of two side plates 8, trapezoidal in shape, with the parallel sides normal to the upper horizontal surface of the bolster and the longer side away from the end of the bolster; the side plates 8 having their edges normal to the parallel sides overhanging the upper surface of the bolster. The two plates are maintained apart by 45 means of tubular portions 9 which register with openings in the plates 8. Engaging these openings and the tubular portions 9 are bolts 10, which bind the two plates rigidly together.

The middle bolt adjacent the longest parallel side of the plates 8 carries a sharply

pointed member 11 pivotally mounted on same and having the sharp point projecting from the said side, so as to engage a log adjacent the bumper. The opposite end of said 60 pointed member 11 is provided with a hooked portion adapted to engage a loop 12 mounted on another bolt 10. The sharp member 11 is prevented from side motion on the bolt 10 by providing on the side of 65 same shortened tubular portions 13. Each of the said plates 8 is also provided with a plurality of cups 14 formed on the exterior surface and all in alinement in a plane parallel to the upper surface of the bolster. 70 The cups 14 are provided with grooves 15 having a threaded aperture engaged by a screw 16. Engaging in the cups 14 is a roller 17, the ends of which are provided with grooves 18 registering with the grooves 75 15 in the cups 14 of the opposite plates. Located in the grooves 15 and in engagement with the grooves 18 is a series of balls 19 forming a bearing for the roller 17. The balls 19 are placed in position in the groove 80 15 through the threaded opening in the cup by removing the screw 16. The rollers 17 when bearing in cups 14 rest on the upper surface of the bolster, and, consequently, form a support for the plates 8. It can be 85 easily seen that when the bumper is caused to move on the bolster the rollers 17 will afford an easy displacement for same, as rolling friction is less than sliding friction.

Intermediate the side of the bolster and 90 the inner face of the plate 8, a longitudinal plate 20 is provided, which is pivotally connected to the lower corner of the longest parallel side of the plate 8. The plate 20 is provided with a longitudinal slot 21, extending substantially through the entire 95 length of the plate, and a series of notches 22, substantially normal to the groove 21 and communicating therewith. The bolster 6 is provided with an elongated side opening 100 into which a key 23 fits. The key 23 is provided with cam surfaces 24 registering with the slot 21 of the plates 20. The opening in the bolster, as above stated, is elongated, so that the key 23 can be extracted or placed 105 in position when end portion 25 is in alinement with the elongation of the opening. Therefore, normally, the sides of the cam 24 are bearing against the sides of the bolster 6. Apertures 26 are provided in the key 110 23 into which pins 27 are fitted. These pins will contact with the exterior surface of the

plates 20 and prevent their displacement on the key.

The width of the cam surfaces 24 is such that when in position indicated in Fig. 1 the notch 22 of the plate 20 cannot pass the same; while in position indicated in Fig. 1 it can easily enter the notch, and the plates 20 can fall to the position indicated in Fig. 2. A clevis 28, extending transversely of the upper surface of the bolster, is pivotally mounted in the plates 8, and, normally, when the bumper is in the operative position the clevis rests on the upper surface of the bolster. A groove 29 is provided in the upper surface of the bolster, near the end of same. The reason for this will appear hereinafter.

The operation of my bumper is as follows: When the first row of logs is placed on the upper surface of the bolster, the pointed member 11 is placed as shown in Fig. 1 and the bumper is drawn or pushed against the log. The key 23 being maintained in position shown in Fig. 1 allows the notches 22 of the plate 20 to jump consecutively until the member 11 engages the log. The key 23 prevents reverse movement of the bumper when in position shown in Fig. 1. The following rows of logs can then be placed. To prevent the rotation of the key 23 in the bolster the head 30 of the key is provided with an opening 31, which opening is engaged by a hook 32 secured to the bolster. This will prevent the rotation of the key in the bolster. It can be easily seen that when in position as shown in Fig. 1, the prism of logs positioned on the bolster will tend to force the bumper off the bolster, and, necessarily, the plate 20 will pull on the key 23 preventing the displacement of the bumper from the bolster. Simultaneously, the pointed member 11 engaged in the adjacent log will prevent longitudinal displacement of the log of the bolster. When it is desired to discharge a load of logs from the bolster, the loop 12 is disengaged from the member 11 and the hook member 32 is disengaged from the key member 23. The key is turned slightly so as to raise the plates 20 and turn the key to the position indicated in Fig. 2. Under the action of the load the bumper will roll on the upper surface of the bolster; and as the key 23 is in position as indicated in Fig. 2 the plate 20 cannot drop into position of Fig. 1 as the notches are not wide enough to engage the cam 24 of the key 23. The rolling motion of the bumper will cause the same to roll off the surface and take the position indicated in Fig. 2, with the clevis 28 engaging the groove 29 provided on the upper surface of the bolster and causing the rollers 17 to abut against the inclined end of the bolster 6. In this position the bumper will direct the rolling logs away from the wagon.

Having thus described my invention, what I claim as new and desire to secure by Letters Patent is:

1. In combination with a wagon bolster, a bumper comprising collapsible means adapted to roll on top of the bolster; means connecting said bumper to said bolster and adapted to make said bumper stationary or movable or cause it to collapse from the top of the bolster. 70

2. In combination with a wagon bolster, a bumper comprising a member adapted to roll on top of the bolster; means engaging the sides of the bolster; a key connecting said side means to the bolster, said side means having means therein co-acting with said key whereby said rolling member when supporting the load may be caused by the same to roll on the bolster and roll off from the top of same against the end of the bolster. 80

3. In combination with a wagon bolster, a bumper comprising a member having means whereby it is adapted to roll on top of the bolster and pivotal means secured to said member and adapted to engage the sides of the bolster; and a key engaging said side means and the bolster, said key and said side means having means whereby the said member can be made stationary or movable on the bolster, said member being adapted when rolling on the bolster to roll off the top of same and rest against the end of the bolster. 90

4. In combination with a wagon bolster, a bumper comprising two plates; means connecting said plates together; rollers intermediate said plates resting on the top of the bolster; a sharply pointed member pivotally mounted between the plates; longitudinal plates pivotally connected to said plates and bearing against the sides of the bolster; and a key having cam portions connecting said longitudinal plates to the bolster, said longitudinal plates having means adapted to co-act with said cam portions on said key, whereby said bumper is made stationary or movable on the bolster. 100

5. In combination with a wagon bolster, a bumper comprising a structure resting on top of the bolster formed by two plates; means for connecting said plates together; rollers intermediate said plates adapted to roll on top of the bolster and a clevis pivotally engaging said plates and resting on top of the bolster; longitudinal plates contacting with the sides of the bolster in pivotal connection with said structure; and a key connecting said plates to said bolster, said longitudinal plates and key having means whereby said structure and longitudinal plates can be made stationary or movable on the bolster, the bolster having a groove near the end thereof adapted to engage said clevis when said structure rolls 110

off the top of the bolster, said engagement of said clevis with said groove causing the said rollers of the structure to contact with the end of the bolster, thereby maintaining 5 said structure in a predetermined position.

6. In combination with a wagon bolster, a bumper comprising two facing plates each having a plurality of cups; ball bearings in said cups; rollers intermediate said facing plates in engagement with said cups and bearing in said ball bearings; means binding 10 said facing plates together, said rollers

carrying said facing plates on the bolster; and means connecting said bolster to said bumper and whereby the position of said 15 bumper on the bolster is controlled.

In testimony whereof I have signed my name to this specification in the presence of two subscribing witnesses.

WILLIAM F. JONES.
